UNITED STATES PATENT OFFICE.

LOUIS ROTH, OF NEW YORK, N. Y., ASSIGNOR TO STERLING BRONZE COMPANY, OF NEW YORK, N. Y., A CORPORATION OF NEW YORK.

OPERATING MEANS FOR SASH ADJUSTERS.

Application filed December 16, 1921. Serial No. 522,868.

To all whom it may concern:

Be it known that I, LOUIS ROTH, a citizen of Austria-Hungary, residing at the city of New York, county of Bronx, and State of New York, have invented a certain new and useful Operating Means for Sash Adjusters, of which the following is a specification.

This invention is an operating device for use in connection with means for imparting movement to a sliding sash.

As is well known, it is customary in some makes or styles of automobiles to employ a sash (one or more) in the body of the car for closing a window opening, and it is usual, also, to associate with said sash appropriate means of one form or another for raising and lowering the same.

My improvement is directed, more particularly, to the member for effecting the manual operation of the sash adjuster, and to the means whereby said member is mounted for service within the car body.

The object is to provide an operating member which is not affected by the jar and vibration inherent in the movement of the vehicle, and the parts of which operating member are interchangeable with corresponding parts of similar operating members, which interchangeability of parts enables the operating member to be assembled and mounted with ease and facility.

To these ends my invention embodies a base member provided with a bearing and with an opening for the reception of a retainer, a shaft actuator having a handle and a bushing unitary one with the other, said bushing being provided with an annular groove and being mounted for free rotative movement within said bearing, a retainer occupying the opening to the base member and fitting in the groove for precluding endwise displacement of said bushing, and a collar fitted to the base member in co-operative relation to the retainer so as to confine it in the opening and prevent displacement under the jar or vibration of the vehicle and to prevent said retainer from dropping out of position by the operation of the device.

Other functions and advantages of the invention will appear from the annexed description taken in connection with the drawings, wherein—

Figure 1 is a view partly in elevation and partly in vertical section of my operating means for a sash adjuster.

Figure 2 is a transverse section in the plane of the dotted line 2—2 of Figure 1.

Figure 3 is an elevation of the base member detached, and

Figure 4 is a detail perspective view of one form of retainer.

The base member A is a single piece provided with a boss a extending outwardly from the face plate a'. Said member is adapted for fixed attachment to the car body 65 interiorly thereof, and to this end, the face plate is provided with a desired number of apertures b through which screws b' pass so as to be embedded in the car body, see Figure 1. The boss of said base member is 70 externally threaded for a part of its length, as at c, and said boss is provided also with an opening d extending through said male threaded part c, said opening being shown in the form of a slot, see Figures 2 and 3. 75 The base member A is a fixed part of the operating device, and the boss a serves as a bearing within which is rotatably mounted a member of the shaft actuator.

Said shaft actuator comprises a bushing 80 B and a crank handle C, the same being of unitary construction by casting said parts in one piece or by uniting the bushing and the crank handle in fixed permanent relation. The bushing is provided with an axial 85 opening e of angular or square form in cross section, the external diameter of said bushing corresponding substantially to the internal diameter of the boss a, whereby the bushing is fitted snugly within the boss so as to substantially preclude all lost motion or 90 idle play while at the same time the bushing is free to rotate within the boss. The length of the bushing is equal substantially to the thickness of the face plate and 95 the length of the boss, whereby in assembling the shaft actuator relatively to the base member the face of the crank handle is in abutting relation to the end of the boss, whereas the inner end face of the bushing 100 is flush, or substantially so, with the inner face of the face plate, see Figure 1.

It is important to preclude accidental separation of the shaft actuator from the base member, thus overcoming relative displacement of the parts by the jar and vibration of the vehicle. In my invention, this function is attained by a retainer D co-operating with the bushing of the shaft actuator. As shown, the retainer is in the 110

Patented Apr. 24, 1923.

1,452,617

UNITED STATES PATENT OFFICE.

WALTER E. SANGER, OF NEW YORK, N. Y., ASSIGNOR TO WILLIAM GARRIGUE & COMPANY, INC., OF NEW YORK, N. Y., A CORPORATION OF NEW YORK.

PROCESS OF AND APPARATUS FOR DISTILLING LIQUIDS.

Application filed March 9, 1921. Serial No. 450,998.

To all whom it may concern:

Be it known that I, WALTER E. SANGER, citizen of the United States, and resident of New York, in the county of New York and 5 State of New York, have invented certain new and useful Improvements in Processes of and Apparatus for Distilling Liquids, of which the following is a specification.

My invention relates to a process of, and 10 apparatus for distilling liquids, and the same is particularly well adapted for use in connection with liquids which show a tendency to partially decompose when distilled directly or alone at normal pressure. Such liquids are distilled in a partial vacuum, whereby 15 the boiling point of the liquids is lowered in accordance with the degree of exhaustion. My improved process is particularly adapted for use in distilling crude glycerine but 20 it is not limited to such use. The improved apparatus which is comprised within my invention is particularly adapted for practising the process described herein.

My invention may be considered as in 25 some respects an improvement upon that disclosed in Patent #774171 granted November 8, 1904, to William E. Garrigues, in which is disclosed a process of distilling liquids such as glycerine in which the water 30 vapors carried over with the distilling liquid in a previous distillation are re-evaporated at less than atmospheric pressure. The steam so produced is superheated by transfer of heat thereto from the vapors of the distilling liquid, this latter being condensed at 35 least in part as it gives up its heat to the steam, and the steam is injected into the body of liquid to be distilled to aid in the evaporation of the liquid in the still.

40 In the actual practise of glycerine distillation in accordance with the disclosure of the patent a comparatively small amount of glycerine is actually condensed in the superheater in which the vapors of the distilling 45 liquid give up heat to the water vapors which are subsequently injected into the still. Accordingly there was a considerable amount of glycerine which was carried along to the evaporator in the form of a dilute glycerine 50 solution called sweet water. This sweet water had to be concentrated and again distilled in order to make the glycerine content thereof effective in the form of dynamite glycerine or the like.

55 I have found that I can control the amount

of glycerine which it is possible to obtain in the form of dynamite grade glycerine, by subjecting the uncondensed glycerine vapors and water vapors mixed therewith to a cooling medium at a stage of the process subsequent to that in which the glycerine vapors pass through the superheater condenser and thereafter condensing the remaining vapors at a different point, to form the sweet water which is then progressed to the evaporator in a continuous process. I find that by the use of this additional condensing step, and by suitably regulating the supply of comparatively cool water vapors in the superheater condenser and of the cooling medium in the condenser next beyond the superheater condenser, I can operate upon either high grade or low grade glycerine to obtain glycerine of dynamite grade. To state the matter more broadly, I fractionate 75 distillates, in a process of the character referred to by utilizing a series of condensing steps, controlling the cooling medium at each step, and collecting the fractions of distillate produced.

80 The objects of my invention accordingly are the provisions of an improved process of the character referred to and the provision of improved apparatus whereby greater efficiency is obtained in a process of the character generally referred to above.

85 In order that a better understanding of my invention may be had, attention is hereby directed to the accompanying drawings forming part of this application and illustrating one embodiment of my invention. In the drawings, Fig. 1 represents a diagrammatic side elevation of the apparatus included in my invention and used for practising my improved process, certain parts 90 being shown in section, and Fig. 2 is a similar view of a portion of the apparatus, on an enlarged scale.

95 Referring to the drawings, the still 1 of any suitable form contains the raw product such as crude glycerine which may be automatically fed into the still as required. It may be heated by any suitable means such as the steam coil 2 partly immersed in the raw liquid. The still may additionally be 100 heated by any external source of heat in the usual manner.

105 Inside the still there is a pipe 3 to carry the superheated steam or vapors which are to be injected into the raw material in the 110

still to aid the distillation of the same. At the lower end of pipe 3, there is preferably provided a spider 4 provided with a number of perforations or openings through which the superheated vapors pass into the crude liquid. Preferably a plurality of spider arms are provided which are preferably closed at the ends but may be left open if desired.

- 10 In the apparatus shown in the drawings the evaporator 5, which is suitably heated, is adapted to evaporate water, such as the "sweet water" which has been obtained by condensing the water vapors carried over 15 with the vapors of the distilling liquid in a previous distillation. The water vapors produced in evaporator 5 pass upwardly by pipe 6 into the superheater condenser 7 which may be provided with a series of 20 tubes 8 and baffle plates 9. In the superheater condenser there is a transfer of heat from the vapors of the distilling liquid which pass upwardly from still 1 through pipe 10, to the water vapors which have entered the superheater condenser from pipe 6. The water vapors may pass through the tubes 8 and the vapors of the distilling liquid pass around the tubes 8 or vice versa. In the apparatus shown in the drawings the 30 water vapors pass through the tubes 8 while the vapors of the distilling liquid pass around the tubes. The water vapors are considerably cooler than the vapors of the distilling liquid as will be explained more 35 fully hereinafter. Accordingly the vapors of the distilling liquid are partly condensed and the water vapors are superheated. These superheated water vapors pass out of the superheater condenser by pipe connection 40 11 which carries the same into the still, the superheated water vapors then continuing downwardly through the pipe connection 3 to a point near the bottom of the crude liquid in the still.
- 45 To describe briefly the other chief apparatus shown in the drawings, the tank or receiver 12 is connected by pipe connection 13 to the bottom of the superheater condenser 7. A pipe connection 14 extends upwardly from receiver 12 and connects with the upper portion of a condenser 15 which I term a cooler condenser, which is connected at the bottom by pipe 16 with its receiver 17. A pipe connection 18 extends 50 upwardly from receiver 17 to a connection shown at 19 with a third condenser 20 which latter is connected at the bottom by pipe 21 with a receiver 22. Receiver 22 is connected at the bottom by pipe 23 with the 55 evaporator 5.

A concentrator 24 is adapted to receive distillates collected in receivers 12 and 17. These receivers may be connected by couplings 25 and 26, with the pipe 27 leading to the concentrator as shown. The up-

per portion of concentrator 24 is shown as connected by pipe 28 with the connection 19 leading into the upper portion of condenser 20. A vacuum pump 29 is connected to the system in such manner that all parts 70 of the same may be placed under reduced pressure. As shown in the drawings the pump 29 is connected by pipe 30 with the receiver 22 which latter is connected by pipe 23 to the evaporator 5 as noted above. 75

The evaporator 5 is heated by suitable means, such for example as the coil 31 shown as mounted within the same. This coil may be heated by the passage therethrough of exhaust steam from the coil 2 within still 1, the exhaust end of coil 2 being connected to the entrance end of coil 31 by pipe connection 32. Evaporator 5, might, of course, be heated by any other suitable means such for example as steam supplied directly from a boiler or by the exhaust steam from the pump 29. With the construction shown in the drawings, the coil 2 in the still may contain condensed water at its lower end. If that is so this water is under high pressure 90 until it passes the throttle valve 33 which is located between the outlet of coil 2 and the inlet of coil 31. After the water condensed in the still coil passes throttle valve 33 the water is under less pressure and a part of the same "flashes" into steam which is available for heater purposes in the evaporator. 95

Assuming that, for instance, glycerine is to be required, the crude glycerine is fed automatically into the still to which external heat is preferably applied. Air is now exhausted from the entire apparatus by means of vacuum pump 29. Evaporator 5 contains water or is filled with so-called sweet water from a previous distillation. As stated, this is heated by any suitable means, preferably by the submerged coil 31. Under the reduced pressure existing in the apparatus the sweet water in the evaporator boils easily 100 and the vapor passes out through pipe 6 into the superheated condenser 7. Here it passes through the tubes 8 and is superheated by the vapor of glycerine and steam which pass upwardly from the still through pipe 10 and passes around the condenser tubes 8, the baffle plates 9 being preferably provided to cause the vapors to follow a circuitous path as they pass around the condenser tubes. 105

As the sweet water vapor which passes upwardly from the evaporator is saturated steam produced in a vacuum, its temperature is considerably below 212° F. The vapors coming from the still, however, have a temperature of about 325° F. the heat of the still being so regulated as to maintain these vapors at about that temperature. Accordingly there is a great difference in temperature between the hot glycerine and steam vapors coming from the still and the sweet water vapor coming from the evaporator. 115 120 125 130

Accordingly the sweet water vapors act as a condensing medium and a part of the glycerine will accordingly be condensed in the superheater condenser 7. The amount 5 of glycerine so condensed is controlled by the amount of the comparatively cool vapors rising from the evaporator. If the amount of comparatively cool vapors is increased, the amount of glycerine condensed 10 is increased, and if the amount of comparatively cool vapor is decreased the amount of glycerine condensed at this point is decreased. The rate at which water vapors are generated in evaporator 5 will be controlled by the amount of evaporating surface 15 provided in the evaporator and the temperature which is there maintained.

The water vapors which have been superheated in condenser 7 as stated, pass downwardly into the still through pipe connection 3 and are distributed throughout the crude glycerine in the still by means of the perforations in the spider arms 4. The steam thus injected causes the hot glycerine 25 to distill over through the pipe connection 10 as stated.

It will be noted that the pipe connection 3 extends downwardly through the still from the top thereof in the arrangement shown 30 so that the steam contained in pipe 3 is still further superheated by the vapors of the distilling glycerine as they pass upwardly through the still on their way to the pipe connection 10. The superheating of the 35 steam which is injected into the crude glycerine in the still is therefore partly accomplished in the still itself and partly in the superheater condenser 7.

The part of the glycerine which is condensed 40 in condenser 7 drops into the receiver 12 from which it passes through pipe 27 into the concentrator 24. Most of the water vapor which is carried along with the glycerine vapor does not condense in the 45 superheater condenser but passes along together with the remaining uncondensed glycerine through pipe 14 into the surface condenser 15, which I term the cooler condenser.

Condenser 15 preferably contains a series 50 of cooling tubes through which water passes, being admitted to the tubes through pipe 34 and passing out of the condenser by pipe 35. The rate at which the cooling water flows through the condenser may be regulated 55 by valve 36. Most of the glycerine which has remained uncondensed is condensed at this point together with a part of the water vapors, the condensed glycerine and water dropping into receiver 17 from 60 which this condensate passes through connections 26 and 27 to concentrator 24 where the glycerine is to be concentrated to form the finished product.

The remaining uncondensed water vapor, 65 with a small percentage of uncondensed gly-

cerine, passes from receiver 17 through connection 18 into the condenser 20. This is preferably a surface condenser the tubes of which may be cooled by water. The water vapor which passes into this condenser 70 through connection 19, contains some glycerine as stated together with certain impurities such as fatty acids and trimethylene-glycol. All of these vapors are condensed in condenser 20 to form the liquid which is 75 known as sweet water. This drops into receiver 22 from which it passes through pipe 23 into the evaporator, from which the water vapors again rise and circulate through the system in the manner described whereby a 80 continuous circulation is created and a continuous process is obtained.

The small quantity of glycerine passing over with the water vapor gradually accumulates in the evaporator 5. When the accumulation 85 is sufficient to justify it, a valve, such as the valve 37, is closed, stopping the feed of sweet water to the evaporator until the water therein has been evaporated. The glycerine remaining in the evaporator is 90 then removed and constitutes a finished product or may be further purified by redistillation.

A trap 38 is preferably interposed in the path by which the vapors of distilling liquids 95 pass from the still into superheater 7. The vapors rising through pipe 10 usually carry certain impurities suspended therein such as salt which may be mechanically separated from the vapors by interposing baffle 100 plates or the like in the path of the vapors. In the construction illustrated, pipe 10 enters trap 38 at one side thereof, the connection from the trap to the superheater taking the form of a pipe 39 which connects 105 the top of the trap with the top of the superheater. Pipe 39 extends downwardly into the trap and is provided at its lower end with a portion 40 preferably of a conical section the lower end of which is covered by a perforated plate or screen 41. The impurities mentioned such as salt are stopped by this screen and drop through pipe 42, back into the still. The object in providing 110 the tapered section 40 is to permit the cross sectional area of the openings in screen 41 to be approximately the same as that of the pipe 39 above tapered section 40.

The concentrator 24 is preferably provided with a heating coil 43. Means are also 115 preferably provided for introducing open steam into the lower part of concentrator 24, a steam pipe 44 being illustrated as leading into the concentrator in which it is provided with perforations.

If by any cause an impurity such as trimethylene-glycol is run into the concentrator with the glycerine, this substance may be distilled from the concentrated solution of glycerine containing this impurity, by in- 120 125 130

jecting open steam through the perforated coil 44 which is located below the level of the liquor in the concentrator. If, for example, the concentrated glycerine solution in the 5 concentrator tests 1.256 in specific gravity at $15\frac{1}{2}$ ° C., the impurity of lower specific gravity may be distilled off through pipe 28 into condenser 20 with open steam as stated and there may be obtained in the concentrator a 10 finished glycerine of dynamite grade with a specific gravity of 1.262 or more at $15\frac{1}{2}$ ° C.

It is thought that the operation of my process will be clear from the above. If the crude glycerine which is to be distilled is a 15 comparatively high grade product, nearly half of the same may be condensed in the superheater condenser 7 and an equal fraction in the surface condenser 15. Thus, in actual 20 practice about 48% of the glycerine in such a case is usually condensed in condenser 7, and 48% in condenser 15, the remaining 4% of the glycerine passing on and into evaporator 5 in the sweet water. In this operation the cooling water is caused to pass through condenser 15 at a comparatively high rate.

If the glycerine is condensed from a lower grade of crude glycerine it is necessary to allow the impurities carried by the same to pass beyond the cooler condenser 15 into the 30 condenser 20. The amount of vapor which is condensed in condenser 15 is somewhat less than in the distillation of the high grade crude product and accordingly the condenser 15 will be supplied with a smaller amount 35 of cooling water, by reducing the opening through valve 36. If the crude product contains 5% of impurities for example, I consider it good practice to condense approximately 48% of the glycerine in condenser 7 and 43% in condenser 15, the remaining 40 4% of the glycerine remaining in the sweet water.

It will, of course, be obvious that my process is not limited in its applicability to the 45 distillation of glycerine, but that the same may be used in distilling or fractionating other liquids which are distilled by steam or water vapors and particularly such liquids which show a tendency to partially decompose when distilled directly or alone at normal pressure.

It should be noted that my invention is not limited strictly to the various details of the 55 process and of the apparatus which have been particularly described but that the same is as broad as is indicated by the accompanying claims.

What I claim is.

1. In distilling apparatus, the combination 60 of a still, a concentrator, an evaporator, a vacuum pump connected to said evaporator, a superheater condenser, a cooler condenser, connections for passing water vapors from said evaporator through said superheater condenser and into said still, means

for passing vapors of distilling liquid from said still through said superheater condenser, to superheat said water vapors and partly condense said liquid vapors, means for passing the uncondensed liquid vapors 70 into said cooler condenser, to condense a further fraction of said liquid vapors, a third condenser, connected to said cooler condenser for condensing water vapor uncondensed in said first two condensers, connections for 75 leading condensed liquid from said superheater and cooler condensers to said concentrator and a connection for leading condensed water from said third condenser to said evaporator.

2. In distilling apparatus, the combination of a still having an opening at the top thereof, an evaporator, a vacuum pump connected to said evaporator, a superheater condenser, a connection for passing water vapors from said evaporator through said superheater condenser and into the top of said still, said connection extending downwardly through the still and having openings at the lower end thereof, below the liquid level in 90 the still, a connection for passing vapors of distilling liquid from said opening at the top of said still through said superheater condenser, to superheat said water vapors and partly condense said liquid vapors, 95 means for condensing the water vapors carried with said liquid vapors and means for passing the condensed water to said evaporator.

3. In distilling apparatus, the combination of a still having a heating coil therein and a pair of openings in the top thereof, an evaporator having a heating coil therein, connected to the exhaust end of said first mentioned coil, a superheater condenser, a 100 vacuum pump connected to said evaporator, connections for passing water vapor from said evaporator through said superheater condenser and into said still through one of said openings, and connections for passing 105 vapors of distilling liquid from the other of said openings in said still through said superheater condenser.

4. In distilling apparatus, the combination of a still, an evaporator, a vacuum pump connected to said evaporator, a superheater condenser, a second condenser, receivers connected with said condensers, means for regulating the supply of cooling fluid of said second condenser, connections for 110 passing water vapors from said evaporator through said superheater condenser into said still and for passing vapors of distilling liquid from said still into said superheater condenser, a connection from the receiver of 115 said superheater condenser to said second condenser, and means for passing fluid not condensed in said two condensers to said evaporator.

5. In distilling apparatus, the combination 120

of a still, an evaporator, a vacuum pump connected thereto, a superheater condenser, a second condenser, a concentrator, connections for passing water vapors from said evaporator through said superheater condenser into said still and for passing vapors of distilling liquid from said still into said superheater condenser, means for passing liquid condensed in said two condensers into said concentrator, means for passing fluid not condensed in said two condensers into said evaporator, and means for fractionating the distilled liquid in said concentrator.

6. The process of distilling glycerine which comprises, creating water vapors from the sweet water at less than atmospheric pressure, superheating the same by the heat of the vapors of the distilling glycerine, injecting the superheated water vapors into the glycerine to be distilled, partly condensing the glycerine vapors by transfer of heat as the water vapors are superheated, subjecting the uncondensed glycerine vapors and water vapors mixed therewith to a cooling medium at a different point, and so regulating the cooling medium in accordance with the grade of the glycerine treated as to there condense nearly all the remaining glycerine, collecting the glycerine condensed at the two points mentioned passing the remaining vapors to another point and there condensing them.

7. The process of distilling glycerine which comprises creating water vapors from the sweet water at less than atmospheric pressure, superheating the same by the heat of the vapors of the distilling glycerine, injecting the superheated water vapors into the glycerine to be distilled, partly condensing the glycerine vapors by transfer of heat as the water vapors are superheated, subjecting the uncondensed glycerine vapors and water vapors mixed therewith to a cooling medium at a different point and so regulating the cooling medium in accordance with the grade of the glycerine treated as to there condense nearly all the remaining glycerine, passing the remaining vapors to another point and there condensing them, passing the condensed sweet water to the

point at which the sweet water is to be evaporated at less than atmospheric pressure, and collecting the glycerine which has been condensed at the two points mentioned. 55

8. The process of distilling liquids which show a tendency to partially decompose when distilled directly or alone at normal pressure, which comprises, creating water vapors at less than atmospheric pressure, superheating the same by the heat of the vapors of such distilling liquid and thereby condensing a part of said liquid vapors, injecting the superheated water vapors into the crude liquid to be distilled, subjecting 60 the uncondensed vapors of the distilling liquid to a cooling medium at a point different from that at which the first part of said vapors was condensed, so regulating the flow of said cooling medium in accordance with 70 the condition of the liquid treated, as to condense nearly all the remaining liquid at said second point, and collecting the fractions of condensate.

9. The process of distilling liquids which show a tendency to partially decompose when distilled directly or alone at normal pressure, which comprises, creating water vapors at less than atmospheric pressure, superheating the same by the heat of the vapors of such distilling liquid, and thereby condensing a part of said liquid vapors, injecting the superheated water vapors into the crude liquid to be distilled, subjecting 75 the uncondensed vapors of the distilling liquid to a cooling medium at a point different from that at which the first part of said vapors was condensed, causing the flow of said water vapors at the point where they receive heat from the vapors of the distilling liquid to proceed at a desired rate, and regulating the flow of said cooling medium at the said different point to determine the proportion of liquid condensed at each 80 point, collecting the fractions of condensate, 90 and progressing the remaining vapors, to the point at which the water vapors at less than atmospheric pressure are created. 95

Signed at New York, in the county of New York and State of New York, this 8th 100 day of March, A. D. 1921.

WALTER E. SANGER.
